UNITED STATES PATENT OFFICE

GEORGE P. GOULDING, DANIEL CLARK, AND THOMAS DICKINSON, OF BUFFALO, NEW YORK.

IMPROVEMENT IN FOG-SIGNALS.

Specification forming part of Letters Patent No. **59,589**, dated November 13, 1866.

To all whom it may concern:

Be it known that we, GEORGE P. GOULDING, DANIEL CLARK, and THOMAS DICKINSON, of the city of Buffalo, county of Erie, and State of New York, assignors to themselves and F. G. Mauser, have invented a new and improved Fog-Signal for Sailing Vessels; and we do hereby declare that the following is a full and exact description thereof, reference being had to the accompanying drawings, making a part of this specification, in which—

Figure I is a front elevation, and Fig. II is an end elevation, of the same.

The nature of this invention consists, first, in the construction of an automatic air-whistle, and the application and use thereof on ship-board, the sounds thereof indicating the course of the vessel and the tack she is sailing on; second, in the combination of a time-piece, or the mechanism of a time-piece, for the purpose of insuring regularity and precision in giving the signals; third, in specific devices, as hereinafter described and claimed.

Letters of like name and kind refer to like parts in each of the figures.

A represents a cylindrical compressed air chamber or reservoir. Air is forced into this chamber through the conducting-pipes b² by means of the air-pumps B B. The air-pumps are of common construction. The pump-rods b¹ connect to overhung cranks C, keyed to the shaft C¹, which is supported in bearings C² and carries a fly-wheel, C³. Motion is given to the shaft C by means of the pinion d¹ on the same and spur-wheel d² upon the shaft D. The shaft D is supported in bearings D³, and is provided, upon each end thereof, with winch-handles d⁴, by means of which the shaft may be revolved and the air-pumps thereby operated and the reservoir A filled with compressed air.

E represents an air-whistle, which may be constructed like an ordinary steam-whistle. It is connected with an upright cylindrical air-chamber, F, by means of the pipe E¹. A stop-cock, E², is placed in the pipe E¹ for shutting off the supply of air from the air-chamber F to the whistle and opening the same at stated intervals, according to the nature of the signal to be given. The air-chamber F is supplied with compressed air through the pipe F¹, communicating with the reservoir A. The pipe

F¹ is also provided with a stop-cock, F². The stop-cocks E² and F² are connected by means of the levers e³ and f³ and connecting-bar g, and are so constructed that when air is admitted through the pipe E¹ to the whistle E by opening the stop-cock E² the passage of air to the air-chamber F will be stopped by the simultaneous turn of the stop-cock F², so that one opens as the other closes, and vice versa.

The particular signals required to indicate the course of a vessel in foggy weather may be given at stated intervals of, say, five minutes, in the following manner: H represents a time-piece or clock-work, of common construction. 1 2 3 4 represent a train of wheels and pinions similar to that used in the striking part of a clock. It is set in motion by the mainspring contained in the drum i¹ and attached to the axis i², the axis being furnished with a ratchet-wheel, i³, which acts upon the spur-wheel 1 by means of the click i⁴. The wheel 2 of the train is provided with a number of pins, j, (say, eight,) projecting from the side of the wheel and placed at equal distances apart in a circle. When the wheel 2 revolves these pins j, being in contact with a short lever, k¹, extending from the axis k, cause the lever to rise and fall or rock upon its fulcrum.

A long lever, k², is connected to the axis k, the extreme end of which passes through a slot or opening made in the vertical bar g or in a horizontal arm or extension thereof, as shown at g', Fig. II. By this means the rocking motion of the short lever k, imparted thereto by the pins j upon the wheel 2, is communicated, through the lever k² and connecting-bar g, to the levers e³ and f³, giving short signals at regular intervals.

The mechanism for stopping and releasing the train of wheels 1 2 3 4 is located between the dial-plate and the clock-work as shown in Fig. II. It consists of a ratchet-bar, L, supported upon pins l¹ l², projecting from the frame-plate of the clock. These pins pass through slots made in the bar L, permitting a short horizontally-reciprocating movement of the said bar. A flat steel spring, l³, is attached to the frame, as shown at l⁴, and acts upon the bar L in a manner to force it to and retain it in one extreme end of its movement. A lever, m, having its fulcrum at m', is provided with a tooth upon its under side which

engages with ratchet-teeth formed in the upper edge of the bar L.

Another lever, n, having its fulcrum at n', is of a peculiar construction. Its end extends below the end of lever m and is in contact therewith. A branch of the lever n turns upward, and its end is bent so as to come in line with a pin, j', projecting from the wheel 4 of the train. This is for the purpose of stopping and starting the train of wheels.

A signal is given every five minutes in the following manner:

O represents a spur-wheel, which meshes with another spur-wheel, O¹, of equal diameter, fastened to that shaft or axis which carries the minute-hand of the clock. The wheel O, therefore, makes one revolution every hour, and is the prime mover.

Twelve pins, O², project from the side of the wheel O, all being arranged in a circle and placed at equal distances apart. A lever or arm, p, is fastened to the fulcrum of the lever n upon their common axis, and extends downward between two of the pins O² upon the wheel O. Hence, whenever during the revolution of the wheel O a pin, O², passes the end of the lever p, the train of wheels 1 2 3 4 starts and gives the signal.

Instead of twelve pins any number may be placed upon the wheel, thereby varying the intervals between the signals.

These fog-signals are sound-signals, and are given in a manner to indicate the course of the vessel, one note of the whistle meaning "before the wind;" two notes, "port tack," and three notes "starboard tack." These three different signals are produced as follows:

Upon that side of the clock-work where the small steel spring l³ is located the face or dial-plate is extended, as shown at q, and carries a cam, q¹, upon its rear side, the edge of which is in line with the bar L or with the adjustable stop w at the end thereof.

The cam q¹ is made triangular, and its sides are at different distances from the center or fulcrum of the cam, the difference of their said distances from the center being equal to the distance apart of the ratchet-teeth upon the bar L. The axis of the cam q¹ carries upon its front end a hand, q², and figures are placed upon the dial-plate indicating the three different signals.

Upon the axis of the wheel 3, projecting from the frame-plate above the bar L, a pawl, r, is keyed, one end of which is in the form of a tooth, and meshes with teeth cut in the bar L. The other end rests upon a pin, r', projecting from the bar L when the train of wheels is stopped.

The operation of the device for opening and closing the valves or stop-cocks E² and F² may be briefly described as follows: The officer of the deck turns the hand q² so as to point to the figure which indicates the number of notes of the whistle to be given at each signal. All the parts are self-operating. The wheel O being revolved by the clock-work with the

same velocity as the minute-hand of the clock, the pin O², against which the lever p rests, slowly moves the same, and thereby lifts the lever n, and with it the lever m. When the lever m is sufficiently raised to disengage its tooth from the ratchet-teeth of the bar L the spring l³ will force the bar L against the cam q¹. If the cam is so turned as to present the edge farthest from its center the bar L will move only the length of one notch. If the cam is so turned as to present the edge somewhat nearer its center it will arrest the bar L after a movement equal to the length of two notches; and if the cam is so turned as to present that side of its triangle nearest its center it will cause the bar L to move through the distance of three notches. As soon as the bar L is liberated from the notched lever the pin r' will, with the bar L, slip from under the pawl r, allowing it to revolve upon its axis. The train of wheels is thereby released, but is immediately arrested by the pin j' striking against the upturned branch of lever n. At the moment, however, that the pin O² against which the lever p rests passes from under the end of the same, the gravity of the lever n will turn it downward and force the lever p against the next pin O². The pin j' upon the wheel 4 is thereby also released, and the train of wheels is finally started and permitted to give the required signal in the following manner: The pawl r, being keyed to the axis of wheel 3 of the train, revolves with the train, and the end thereof, which is formed in the shape of a tooth, engages with the teeth made in the bar L and moves the bar L away from the cam q¹, one revolution of the pawl being necessary to effect the movement of the bar through the distance of one notch. The lever m holds the bar L in the position to which it is moved by each revolution of the pawl r by dropping into the ratchet-teeth or notches of the bar L. As soon as the bar L has been moved back so that the pin r' occupies its former position the long end of the pawl r will strike the same and the revolutions of the pawl be stopped, and the progress of the train thereby arrested.

The subsequent action of every pin O² upon the lever p will have the same effect, starting the train of wheels, giving the signal, and stopping the train, in the manner before described.

The reservoir A must be constantly supplied with compressed air by means of the air-pumps B. The pipe F¹, which supplies the chamber F with compressed air from the reservoir A, may be provided with a second whistle placed on the top thereof, or the said pipe may be continued without the second whistle, and connected with the pipe E¹ at a point above the stop-cock E².

In case a vessel does not heed the signals given as above described, and both should approach each other too close, an additional signal may be immediately given by the second whistle above described. For this purpose

the captain or officer of the deck may open a stop-cock to be connected with the pipe F^1 , and cause that whistle or (in case the pipe F^1 is connected to the pipe E^1 , as above described) the whistle E to give a signal without interfering with the clock-work which operates the whistle E and gives signals at regular intervals.

A fog-whistle being a desirable and important instrument on board of sailing-vessels, we have constructed the within-described apparatus with a view of supplying the demand therefor. Compressed air, such as used in our fog-whistle, gives an equally loud signal as a steam-whistle; and the whole apparatus, as herein described, may be placed upon the deck of a vessel and boxed up in a space not exceeding three feet in any direction, making it most convenient and simple in its construction and operation.

What we claim as our invention, and desire to secure by Letters Patent, is—

1. The construction of an automatic air-whistle, in connection with an air pump or pumps and air-reservoir, and the application and use thereof on shipboard for the purpose of

giving signals to indicate the course of the vessel and the tack she is sailing on, substantially as described.

2. The combination of train of wheels 1 2 3 4, levers k^1 k^2 e^3 f^3 , and connecting-bar g , or equivalents, with an air-whistle, for the purpose of opening and closing the valves E^2 and F^2 , substantially as set forth.

3. The combination of the wheels O O^1 , arm p , levers m and n , stop-pins j' and r' , pawl r , and ratchet-bar L , or equivalents, with a time-piece and air-whistle, for the purpose of regulating and controlling the intervals at which the signals shall be given, substantially as set forth.

4. The cam q^1 , in combination with the dial-plate q and bar L , for the purpose of enabling the officer of the deck to set the mechanism so as to give any required signal.

GEORGE P. GOULDING.
